SAFETY TRAFFIC SIGNAL BELT

Zigmund E. Freeska, Cleveland, Ohio

Application September 18, 1943, Serial No. 502,940

3 Claims. (Cl. 177—329)

This invention relates to new and useful improvements in a safety traffic signal belt.

More particularly, the invention proposes an article as mentioned above, which is characterized by a flexible belt for engaging about one's waist, or about an object. It is proposed to mount a plurality of lights and signal elements on said belt as traffic signals, and other signals. More specifically, it is proposed to use different colored lamps, such as red and white, or other colors. It is also contemplated to use signal buttons of different colors.

The invention proposes a novel construction for holding the various lights and for supplying the necessary electric current to the lights.

For further comprehension of the invention, and of the objects and advantages thereof, reference will be had to the following description and accompanying drawing, and to the appended claims in which the various novel features of the invention are more particularly set forth.

In the accompanying drawing forming a material part of this disclosure—

Fig. 1 is a front elevational view of a safety traffic signal belt, according to this invention.

Fig. 2 is a view similar to Fig. 1 but illustrated with certain of the parts rearranged.

Fig. 3 is a fragmentary enlarged vertical sectional view taken on the line 3—3 of Fig. 1.

Fig. 4 is a fragmentary elevational view looking in the direction of the line 4—4 of Fig. 3, but drawn on a reduced scale.

The safety traffic signal belt, in accordance with this invention, includes a flexible belt 10 for engagement about one's waist, or other object, and having a front face 11 formed with a pair of spaced longitudinally extending grooves 12. These grooves 12 have their base walls stopping short of the back face of the belt 10. A container 13 for a battery 14 is mounted on the belt 10. This container has a flap 15 which may be opened so that the battery 14 is accessible and may be replaced when desired. The belt 10 is shown provided with a standard buckle 16 upon one end thereof cooperative with a line of openings 17 upon the other end. Other holding means may be provided for attaching the belt in position, as desired.

Electric wires 18 and 19 are mounted along and within the said grooves 12 and extend to and within the container 13 and are respectively attached to the terminals of the battery 14. These electric wires 18 and 19 are held in position by staples 20 or other fastening elements, along their lengths and engaging the material of the belt 10.

A plurality of lamp supporting means 21 are mounted upon said belt 10. Each of said means 21 includes a clip 22 preferably of insulation material, slidably mounted on the belt 10. Each clip 22 extends vertically across the face of the belt 10 and has top and bottom arm portions 23 extending across the top and bottom edges of the belt 10. Each clip 22 includes gripping plates 24 pivotally mounted upon the rear ends of the arms 23 by the hinges 25. A spring 26 is mounted on each hinge 25 and normally urges the gripping plates 24 tightly against the back face of the belt.

A lamp socket 27 is mounted upon the front of each clip 22. A contact 28 is connected with one terminal of said socket 27 and extends into one of the grooves 12 and normally contacts one of said wires, namely, the wire 19. A multiple switch-like contact 29 connects with the other terminal of the socket 27 and extends into the other one of the grooves 12 and releasably contacts the other one of said wires, namely, the wire 18. This contact 29 has an outer offset end 30 by which it may be gripped and pulled outwards a short distance to the dot and dash line position illustrated in Fig. 3.

The contact 29 slidably engages against a contact 31 which is connected by a lead 32 with the shell contact of the socket 27. Another lead 33 electrically connects the end contact of the socket 27 with the said contact 28. Lamps 34 of selected colors are engaged in the sockets 27 of the several lamp supporting means 21. Signal buttons 35 are removably mounted on the belt 10 for the purpose of signaling in daylight, or whenever such signals are feasible.

In Fig. 1 four lamp supporting means 21 are illustrated. These may be shifted along to selected positions on the belt 10 merely by forcing the gripping plates 24 out of contact with the back face of the belt 16 and then moving the lamp supporting means 21 along said belt, as desired. Moreover, one or more of these lamp supporting means 21 may be removed from the belt 10 or additional ones added. In Fig. 2 one of the lamp supporting means 21 has been removed and the remaining ones have been shifted to new positions.

The operation of the safety traffic signal belt 50 is as follows:

The belt may be worn by a traffic officer, pedestrian, or others. The signal lamps and signal buttons are arranged to give proper traffic or other signals. For example, the belt may be arranged so that one or more red lights or but-

tons are at the back of a person and one or more white lights are in front. The lights may be shifted to selected positions merely by shifting the lamp supporting means 21. Lamp supporting means 21 may be added or removed as desired.

One or more of the lamps 34 may be turned out by pulling the contact 29 of the particular lamp supporting means outwards so as to disconnect its contact 29 from the wire 18.

The current flows from the terminals of the batteries along the leads 18 and 19 and then in parallel through one or more of the lamps 34.

While I have illustrated and described the preferred embodiments of my invention, it is to be understood that I do not limit myself to the precise constructions herein disclosed and the right is reserved to all changes and modifications coming within the scope of the invention as defined in the appended claims.

Having thus described my invention, what I claim as new and desire to secure by United States Letters Patent is:

1. A safety traffic signal belt, comprising a flexible belt for engaging about one's waist or about an object and having a front face formed with a pair of spaced longitudinally extending grooves, a container for a battery mounted on said belt, electric wires mounted along and within said grooves and extending within said container for connecting said battery with a lamp supporting means slidably mounted on said belt and comprising a clip of insulation material slidably mounted on said belt, a lamp socket on said clip, a contact from one terminal of said lamp socket extending into one of said grooves and contacting one of said wires, and a movable switch like contact from the other terminal of said lamp socket extending into the other of said grooves and releasably contacting the other of said wires, said clip having a front section extending vertically across the front of the belt and top and bottom arms extending across the top and bottom edges of the belt.

2. A safety traffic signal belt, comprising a flexible belt for engaging about one's waist or about an object and having a front face formed

with a pair of spaced longitudinally extending grooves, a container for a battery mounted on said belt, electric wires mounted along and within said grooves and extending within said container for connecting said battery with a lamp supporting means slidably mounted upon said belt and comprising a clip of insulation material slidably mounted on said belt, a lamp socket on said clip, a contact from one terminal of said lamp socket extending into one of said grooves and contacting one of said wires, and a movable switch like contact from the other terminal of said lamp socket extending into the other of said grooves and releasably contacting the other of said wires, said clip having a front section extending vertically across the front of the belt and top and bottom arms extending across the top and bottom edges of the belt, and gripping plates movably mounted upon the rear ends of said top and bottom arms and engaging the back face of said belt.

3. A safety traffic signal belt, comprising a flexible belt for engaging about one's waist or about an object and having a front face formed with a pair of spaced longitudinally extending grooves, a container for a battery mounted on said belt, electric wires mounted along and within said grooves and extending within said container, for connecting said battery with a lamp supporting means slidably mounted upon said belt and comprising a clip of insulation material slidably mounted on said belt, a lamp socket on said clip, a contact from one terminal of said lamp socket extending into one of said grooves and contacting one of said wires, and a movable switch like contact from the other terminal of said lamp socket extending into the other of said grooves and releasably contacting the other of said wires, said clip having a front section extending vertically across the front of the belt and top and bottom arms extending across the top and bottom edges of the belt, and gripping plates movably mounted upon the rear ends of said top and bottom arms and engaging the back face of said belt, and resilient means for urging said gripping plates into operative positions.

ZIGMOND E. FRECSKA.
